Merchant and Kilgore.

UNITED STATES PATENT OFFICE.

MARK ISAACS, OF MINNEAPOLIS, MINNESOTA.

MILK CAN.

Application filed December 6, 1926. Serial No. 152,840.

My invention relates to milk or similar cans, and has for its object to improve the same, as will hereinafter appear, and to this end it consists of the novel devices and combinations of devices hereinafter described and defined in the claims.

In the accompanying drawings, which illustrate the invention, like characters indicate like parts throughout the several views.

10 Referring to the drawings:

Fig. 1 is a plan view of the invention;

Fig. 2 is a fragmentary view partly in side elevation and partly in central vertical section, and further illustrating, by means of 15 broken lines, a second can supported on the cover of the can illustrated by full lines; and

Fig. 3 is a fragmentary detail view with some parts sectioned on the line 3—3 of Fig. 1.

20 The numeral 4 indicates a milk can having a raised bottom 5 with a depending annular channel flange 6 into which the lower end portion of said can is secured. Said can has a contracted top section 7 that terminates in a cylindrical neck 8. At the upper edge of the neck 8 is a radially outstanding rolled bead 9, the top of which affords an annular gasket-engaging surface. Rigidly secured to the contracted can section 7 is a handle 10 and a lock stud 11 diametrically arranged, and said lock stud is provided with a transverse bore 12 for a purpose that will presently appear.

25 A bail 13 for the can 4 is pivoted to a pair of diametrically opposite axially lined shouldered pivot studs 14 secured to the neck 8. Said bail 13, in the vicinity of its pivoted ends, is bent in the direction of its swinging movement to afford a pair of cranks 15 having cam-acting surfaces 16 that are eccentric to the axis of the pivot studs 14.

30 A novel depressed cover 17 is provided for the can 4 and is formed from a single sheet of metal. This cover 17 is provided with a 45 telescoping cylindrical flange 18 adapted to snugly fit in the neck 8 and is folded upon itself at 19 and extended below said cover.

The upper portion of the cover flange 18 is 50 rolled to form a hollow radially outstanding annular rim 20.

The under side of the rim 20 affords a 55 gasket-engaging surface which overlies the bead 9 when the cover 17 is telescoped into the neck 8. A pair of axially aligned dia-

secured to the rim 20 below the top thereof. When the cover 17 is properly positioned in the neck 8, its lock studs 21 are directly over the pivot studs 14. A gasket 22 is applied to the cover flange 18 and arranged to be compressed between the bead 9 and rim 20.

60 The bail 13 is shown in an operative position by means of broken lines in Fig. 2, and in which position it rests on the handle 10 where it may be grasped with said handle to 65 hold the bail when tipping the can 4 to pour the contents therefrom.

65 To lock the cover 17 in the neck 8 and compress the gasket between the bead 9 and rim 20 to form a tight joint between said cover 70 and can 4, the bail 13 is swung from its dotted line position to its full line position, as shown in Fig. 2. During this movement of the bail 13 its cranks 15 are moved over the lock studs 21 and their cam surfaces 16 75 engage said studs. The distance between the cam surfaces 16 and the axis of the pivot studs 14 progressively decreases toward the pivoted ends of the bail 13 so that, during the final movement of the bail 13 to its full line 80 position as shown in Fig. 2, the cam surfaces 16, acting on the cam studs 21, compress the gasket 22 between the bead 9 and the rim 20.

85 A bore 23 is formed in the bail 13 substantially in alignment with the bore 12 in the lock stud 11 when said bail is in an operative position to lock the cover 17 in the neck 8. To prevent the bail 13 from being released while the can 4 is in transit, the same 90 is secured by a wire 24 inserted through the bores 12 and 23 and the ends thereof secured by a lead seal 25.

95 It is important to note that when the bail 13 is operated to lock the cover 17 in the neck 8 it is entirely below the top of the cover 17 so that a second can 26, similar to the can 4, may be supported on said can 4, and rests directly on the cover thereof, as indicated by broken lines in Fig. 2. The bottom flange on the can 26 prevents said can from sliding laterally on the cover of the can 4.

100 A handle for the cover 17 extends diametrically within the flange 18 above said cover and is provided with an aperture 28 through which may be inserted a cord, wire, or other fastening device, for securing a tag to the can for the purpose of identification.

105 The handle 10 and lock stud 11 are so arranged that cans similar to the can 4 may 110

be placed close to said can. By folding the flange 18 upon itself and extending the same below the cover 17, said cover is materially strengthened and reinforced so that the 5 same will keep its shape and not be dented or bent while being handled. The contents of can 4 cannot come into contact with the gasket 22 for the reason that the flange 18 tightly fits within the neck 8 but at the 10 same time said gasket will tightly seal the joint between the cover and can, and by its yielding action under which it is compressed by the bail 13, will tend to keep the cranks 15 securely interlocked with the lock studs 15 21.

The formation of the cover 17 is such that it may be readily cleansed and at which time the gasket 22 may be removed therefrom and also cleansed. The gasket 22, as previously stated, tightly seals the joints between the cover 17 and neck 8 and thus excludes all moisture, dust and other foreign matter from the can. The seal 25 prevents the bail 13 from being operated to release 25 the cover 17 so that the contents of the can 4 cannot be tampered with. The cranks 15 securely hold the cover 17 in the can 4 even under rough handling, and in case the can 4 is upset, will prevent the spilling of its 30 contents.

What I claim is:

1. The combination with a milk can having a depressed cover telescoped into the

neck thereof and provided with a pair of radially projecting axially aligned studs 35 spaced below the top of the cover, a handle in the cover not above the top thereof, said can and cover having co-operating clamping surfaces, and a bail pivoted to the can and having cam-acting cranks arranged 40 to engage said studs by a movement of the bail to press said cover onto the can and lock the same thereto, said bail, when locking the cover on the can, being below the top of said cover to permit a similar can to be supported 45 on said cover.

2. The combination with a milk can having a depressed cover telescoped into the neck thereof and provided with a pair of radially projecting axially aligned studs, a fixed handle on the can, said can and cover having co-operating clamping surfaces, and a bail pivoted to the can and having cam-acting cranks arranged to engage said studs by a movement of the bail to press said cover 50 into the can and lock the same thereto, said bail when moved, into a position to release the cover, being arranged to rest on the handle to be gripped with said handle.

3. The structure defined in claim 2 in 55 further combination with a lock stud on the can adapted to receive a fastener for securing the bail thereto when in a position to lock the cover on the can.

In testimony whereof I affix my signature.

MARK ISAACS.
